Louis Hornberger INVENTOR

BY *Geo. L. Cooper*

ATTORNEY

UNITED STATES PATENT OFFICE.

LOUIS HORNBERGER, OF BRIDGEPORT, ASSIGNOR TO THE EDWARD MILLER & COMPANY, OF MERIDEN, CONNECTICUT.

DESIGN FOR A BASE FOR LAMPS.

SPECIFICATION forming part of Design No. 25,145, dated February 11, 1896.

Application filed December 21, 1895. Serial No. 572,958. Term of patent 3½ years.

To all whom it may concern:

Be it known that I, LOUIS HORNBERGER, a citizen of the United States, residing at Bridgeport, Fairfield county, Connecticut, have invented a new Design for Bases for Lamps and the Like, of which the following is a specification.

The accompanying drawings represent my base, Figure 1 in perspective, and on a smaller scale, Fig. 2, in top plan view.

The invention relates to a design for a base for lamps and other articles; and the design consists in the configuration and ornamentation thereof, as shown in the illustrations.

The base consists of a low convex conical body with four projecting feet. Two of these feet, oppositely placed, project radially and are bilaterally symmetrical. These are ornamented with raised scrolls and a raised middle rib passing up into the body of the base.

The other oppositely-placed feet are considerably curved from a radial line, are symmetrical, and ornamented with scrolls. The alternate quadrants of the body are dissimilar, the opposite ones being similar. The body is of open-work ornamented with medallions, raised ribs and flowers in relief.

The leading feature of my design is the dissimilar alternate feet and open-work quadrant of the body ornamented with medallions, ribs, scrolls, and flowers.

What I claim as my invention, and desire to secure by Letters Patent of the United States, is as follows:

The design for a base for lamps, as herein shown and described.

LOUIS HORNBERGER.
